1,956,636

CHUTE DEVICE FOR ROLLING MILLS

Florence C. Biggert, Jr., Crafton, Pa., assignor to
 United Engineering & Foundry Company, Pittsburgh, Pa., a corporation of Pennsylvania

Application January 13, 1932, Serial No. 586,300

10 Claims. (Cl. 80—51)

- My invention pertains to chute devices such as are employed in rolling mills for guiding the metal from one stand of rolls to another.
- In rolling mill practice it is common to provide chutes for directing the travel of the metal from a stand of rolls to a following stand, and with these chutes are frequently associated what are termed "loopers", that is, devices for taking up any slack which may exist in the metal between the two stands of rolls. The chutes necessarily have portions which reach into close proximity with the rolls of the respective stands, and an objection to them, as heretofore constructed, has been that these portions stand in the way of the rolls and their associated parts when it is desired to remove the latter from the stands for the purpose of regrinding the rolls, changing them or the like. The rolls, and their associated parts, such as the bearing blocks usually termed chocks, have to be removed laterally through "windows" provided for the purpose in the frames of the stands. This requires that any parts of the chutes which stand in line with the openings of the windows must be taken out of the way before the rolls can be removed. Heretofore these parts of the chutes have been moved out of the way by disconnecting them and taking them off the mill, in the case of the heavier parts, by means of a crane or the like. This has entailed much loss of time.
- It is the principal object of my invention to provide a chute device in which the above objection will be eliminated and in which any parts of the chutes which stand in line with the window openings can be easily and quickly moved out of the way. Other objects of my invention and advantages obtained thereby will appear from the specification and claims to follow.
- As an example of one form in which my invention can be embodied, I have shown a chute device constructed in accordance therewith, and having a looper applied thereto, in the accompanying drawings and described the same in the following specification. However, I wish it understood that my invention can be embodied in other forms, and that changes can be made in the form described and shown, without exceeding the scope thereof as defined in the appended claims.
50. In the drawings:
- Fig. 1 is a side elevation of the chute device, the location of the roll stands and rolls being indicated in dotted lines;
- Fig. 2 is a plan, the chutes being shown in full lines as adjusted for guiding a relatively wide
- strip of metal and in dotted lines as adjusted for guiding a relatively narrow strip;
- Fig. 3 is a longitudinal section taken centrally through the device; and
- Fig. 4 is a transverse section taken on the line IV—IV of Fig. 2.
- In the drawings a front stand c is shown, from which the strip of metal being rolled moves to a rear stand c'. The stands carry operating rolls a, a' and bearing rolls b, b', and are provided with "windows" d, d' through which the rolls and associated parts can be removed when this is necessary.
- The chute device comprises supports 10 rigidly secured in position in any desired manner, as by bolting them to the frames of the roll stands. Upon these supports are mounted rails 11, one on each side of the device, which carry a front slide 12 and a rear slide 13. The slides support the chutes and are provided with means whereby they can be moved on the rails towards and from each other, the chutes being constructed so that they can telescope one on the other when the slides are thus moved. In this way any chute portions which may lie in line with the openings of the windows d, d' can readily be moved out of the way, affording room for the removal of the rolls.
- The front slide is in the form of a casting having at its front end a plurality of brackets 14 which support strippers 15 which yieldingly bear upon the lower of the operating rolls a of the front stand. The strippers 15 are loosely mounted in the slots of the brackets 14 and the strippers are thereby permitted to move relative to the brackets so that the vertical positions of the outer ends of the strippers may vary in accordance with the horizontal position of the slide 12 relative to the rolls a. The slide also supports strippers 16 which yieldingly bear upon the upper roll. These parts are generally of a familiar construction, but are so made that they can be moved with the front slide toward and away from the rolls. Pivoted upon pins 17 carried by the front slide is a pair of front chutes 18 provided with side flanges 19. The chutes are formed with channels 20 in which can lie a looper roll 21, gaps 22 being provided in the side flanges 19 to permit of raising and lowering the looper roll.
- The looper roll is mounted in an arm 23 which is pivoted at 24 to the front slide and has connected thereto the upper end of a rod 25. The lower end of the rod is pivoted to a lever 26 operated upon by the rod 27 of a piston in the cylinder 28. The piston in the cylinder 28 is operated in

the usual manner so as to cause the looper roll to bear against the under side of the metal strip, taking up any slack thereof and putting the strip under the desired degree of tension.

5 The front slide has fixed thereto, at its front end, a central support plate 29, and, beyond said support plate, has pivoted thereto a central support bar 30 which forms a continuation of the support plate. The support bar is formed with 10 a channel 31, like the channels of the front chutes, for receiving the looper roll 21.

The rear slide 13 is constituted by a casting which includes a pair of transverse rails 32 upon which are slidably mounted support castings 33.

15 To these castings are secured the rear chutes 34 which are provided with flanges 35 adapted to guide the strip of metal into the rolls *a'* of the rear stand. Such flanges are flared outwardly at their front ends, as indicated at 35a.

20 Rotatably mounted in the rear slide, and disposed beneath the rails 32, are a pair of shafts 36 and 37, of which the latter is driven from the former by means of a chain 38 passing over sprockets on the shafts. The shaft 36 is driven from a motor 39 through a pair of universal joints 40 and 41. The support castings 33 have downwardly extending portions 42 which embrace the rails 32 and have secured thereto, beneath said rails, caps 43. Nuts 44 are mounted in these

25 caps and are threaded upon the shafts 36 and 37, the threads on the shafts being right and left-handed at their respective ends. From this construction it will be noted that when the motor 39 is energized to rotate the shaft 36 the support castings 33 and 34, with the rear chutes which 30 they carry, will be moved either towards or away from each other according to the direction of rotation of the motor. In this manner the rear chutes are adjusted so as to guide into the rolls 40 *a'* of the rear stand strips of varying widths.

40 At their front portions, the rear chutes 34 are bent downwardly, as indicated at 34a, and upon these downwardly bent portions rest the ends of the front chutes 18, in such a manner that the 45 chutes constitute continuations of one another when the parts are in their normal operative position. The rear slide carries a support plate 45 which is likewise bent downward at its front end, as indicated at 45a, to receive the end of the support bar 30 of the front slide.

50 The flanges 35 of the rear chutes are formed with channels 46 which slidably receive the ends of spring clips 47 carried by the front chutes 18, so that when the rear chutes are adjusted inwardly and outwardly the front chutes will rock about their pivots 17 and follow them in their adjustment. When the rear chutes have been adjusted inwardly, to accommodate a very narrow strip, they and the front chutes will take a position such as is indicated in dotted lines in Fig. 2. 55 Rotatably mounted in a housing 48 and extending longitudinally of the apparatus is a shaft 49 which is screw-threaded, in opposite directions, at its ends to enter correspondingly threaded portions 50 and 51 of the front and rear slide respectively. The shaft 49 is driven, through a train of gearing contained in the housing 48, from a shaft 52 actuated by a motor 53. Thus when the motor 53 is energized to rotate the shaft 52 the front and rear slides will be caused either to approach or 60 recede from each other.

65 The normal operative position of the parts is shown in Fig. 1, and it will be seen therefrom that the strippers 15 and 16, brackets 14, etc. associated with the front chutes stand in line with the

opening of the window *d* of the front stand and would prevent removal of the rolls and their chocks from the stand. Likewise the ends of the rear chutes 34 stand in line with the openings of the windows *d'*, and would prevent the removal of the rolls from the rear stand. When, however, it becomes desirable to remove a roll from a stand the motor 53 is operated to cause the front and rear slides to approach each other, the ends of the front chutes riding up the inclines 34a of the rear chutes and along the flared portions 35a of the flanges of the latter. Similarly the support bar 30 rides up the incline 45a of the support plate on the rear slide. When the slides are thus moved towards each other the strippers 15 and other parts which stand in line with the opening of the window *d* are moved forward and out of line with such opening, and the ends of the chutes 34 are moved rearward and out of line with the opening of the window *d'*, thereby taking away any obstacle to the removal of the rolls. When the rolls have been replaced, all that is necessary is to operate the motor 53 in the reverse direction bringing the parts back to their normal operative position. 100 These operations can be carried out regardless of the position to which the rear chutes 34 may have been adjusted, and without affecting the operation of the looper.

I claim:

1. A chute device for employment between a delivering and a receiving stand of a rolling mill, comprising a movably mounted support normally disposed adjacent said delivering stand, a second movably mounted support normally disposed adjacent said receiving stand, a pair of chutes carried by said first-named support, a pair of chutes mounted on said second-named support, and adjustable transversely thereof, and means for moving said supports towards and away from each other.

2. The combination with a rolling mill including a metal delivering roll stand and a metal receiving roll stand, of a chute device disposed between said stands and comprising a movably mounted support normally disposed adjacent said delivering stand, strippers carried by said support and movable therewith, a second movably mounted support normally disposed adjacent said receiving stand, a chute carried by said first-named support and disposed in continuation of said first-named chute, a chute carried by said second-named support, and means for moving said supports towards and away from each other, whereby said strippers may be moved from operative position into a position permitting withdrawal of the rolls of said delivering stand.

3. A chute device for employment between a delivering and a receiving stand of a rolling mill, comprising a movably mounted support normally disposed adjacent said delivering stand, a movably mounted support normally disposed adjacent said receiving stand, a pair of chutes carried by said second-named support and having portions for guiding the metal into said receiving stand, means for adjusting said chutes transversely of said second-named support, a pair of chutes pivoted to said first-named support, said second-named chutes being connected with said first-named chutes so as to be rocked about their pivots when said first-named chutes are adjusted, and means for moving said supports towards and away from each other.

4. A chute device for employment between a delivering and a receiving stand of a rolling mill,

- comprising a movable support normally disposed adjacent said receiving stand, a pair of chutes carried by said support, means for adjusting said chutes transversely of said support, a second movable support normally disposed adjacent said delivering stand, a pair of chutes movably mounted on said second-named support and slidably connected with said first-named pair of chutes so as to participate in the adjusting movement of the latter, and means for moving said supports towards and away from each other. 80
5. A chute device for employment between a delivering and a receiving stand of a rolling mill, comprising a movable support normally disposed adjacent said receiving stand, a pair of chutes carried by said support, means for adjusting said chutes transversely of said support, a movable support normally disposed adjacent said delivering stand, a pair of chutes each pivoted at one end to said second-named support and slidably connected at the other end with one of said first-named chutes, and means for moving said supports towards and away from each other. 85
10. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 90
15. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 95
20. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 100
25. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 105
30. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 110
35. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 115
40. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 120
45. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 125
50. A chute device for employment between a delivering and a receiving stand of a rolling mill, comprising a track disposed between said stands, a support slidably mounted on said track and normally disposed adjacent said receiving stand, a pair of chutes carried by said support and having portions for guiding the metal into said receiving stand, a support slidably mounted on said track and normally disposed adjacent said delivering stand, a pair of chutes pivoted to said second-named support at the ends thereof adjacent said delivering stand and slidably connected with said first-named chutes at their other ends, whereby said second-named chutes participate in the adjusting movement of said first-named chutes, and means for moving said supports towards and away from each other. 130
6. A chute device for employment between a delivering and a receiving stand of a rolling mill, comprising a longitudinally movable chute for receiving the metal from said delivering stand, a second longitudinally movable chute for directing the metal to said receiving stand, said second-named chute being disposed in continuation of said first-named chute, and means for moving said chutes towards and away from each other to thereby respectively retract them from, and advance them toward, the adjacent roll stands. 135
7. The combination with a rolling mill including a metal delivering roll stand and a metal receiving roll stand, of a chute device disposed between said stands and comprising a movable support normally disposed adjacent said receiving stand, a chute carried by said support, said chute having a downwardly inclined portion at the end thereof remote from said receiving stand, a movable support normally disposed adjacent said delivering stand, a chute carried by said second- 140
- receiving stand, a longitudinally movable chute carried by said first-named support, a longitudinally movable chute carried by said second-named support and disposed in continuation of said first-named chute and means for moving said supports horizontally towards and away from each other to thereby respectively retract the chutes from, and advance them toward, the cooperating roll stands. 145

CERTIFICATE OF CORRECTION.

Patent No. 1,956,636.

May 1, 1934.

FLORENCE C. BIGGERT, JR.

It is hereby certified that error appears in the printed specification of the above numbered patent requiring correction as follows: Page 2, lines 126 and 127, claim 2, strike out the words "and disposed in continuation of said first-named chute" and insert the same after "support" in line 128; and that the said Letters Patent should be read with this correction therein that the same may conform to the record of the case in the Patent Office.

Signed and sealed this 19th day of June, A. D. 1934.

Bryan M. Battey

(Seal)

Acting Commissioner of Patents.

- comprising a movable support normally disposed adjacent said receiving stand, a pair of chutes carried by said support, means for adjusting said chutes transversely of said support, a second 5 movable support normally disposed adjacent said delivering stand, a pair of chutes movably mounted on said second-named support and slidably connected with said first-named pair of chutes so as to participate in the adjusting movement of the latter, and means for moving said supports towards and away from each other. 80
- 10 5. A chute device for employment between a delivering and a receiving stand of a rolling mill, comprising a movable support normally disposed adjacent said receiving stand, a pair of chutes carried by said support, means for adjusting said chutes transversely of said support, a movable support normally disposed adjacent said delivering stand, a pair of chutes each pivoted at one 15 end to said second-named support and slidably connected at the other end with one of said first-named chutes, and means for moving said supports towards and away from each other. 85
- 20 6. A chute device for employment between a delivering and a receiving stand of a rolling mill, comprising a track disposed between said stands, a support slidably mounted on said track and normally disposed adjacent said receiving stand, a pair of chutes carried by said support and having 25 portions for guiding the metal into said receiving stand, a support slidably mounted on said track and normally disposed adjacent said delivering stand, a pair of chutes pivoted to said second-named support at the ends thereof adjacent said 30 delivering stand and slidably connected with said first-named chutes at their other ends, whereby 35 said second-named chutes participate in the adjusting movement of said first-named chutes, and means for moving said supports towards and away 40 from each other. 90
- 45 7. The combination with a rolling mill including a metal delivering roll stand and a metal receiving roll stand, of a chute device disposed between said stands and comprising a movable support normally disposed adjacent said receiving stand, a chute carried by said support, said chute having a downwardly inclined portion at the end thereof remote from said receiving stand, a movable support normally disposed adjacent said 50 delivering stand, a chute carried by said second- 95
- named support and resting, at its end remote from said delivering stand, upon the downwardly inclined portion of said first-named chute, and means for moving said supports towards and away from each other. 100
8. A chute device for employment between a delivering and a receiving stand of a rolling mill, comprising a movable support normally disposed adjacent said receiving stand, a pair of chutes mounted on said support and adjustable transversely thereof, each of said chutes having a downwardly inclined portion at the end thereof remote from said receiving stand, a movable support normally disposed adjacent said delivering stand, a pair of chutes pivoted to said second-named support at the ends thereof adjacent said delivering stand and resting at their other ends upon the downwardly inclined portions of said first-named chutes, and means for moving said supports towards and away from each other. 105
9. The combination with a rolling mill including a metal delivering roll stand and a metal receiving roll stand, of a chute device disposed between said stands and comprising a longitudinally movable chute for receiving the metal from said delivering stand, a second longitudinally movable chute for directing the metal to said receiving stand, said second-named chute being disposed in continuation of said first-named chute, and means for moving said chutes towards and away from each other to thereby respectively retract them from, and advance them toward, the adjacent roll stands. 110
10. The combination with a rolling mill including a metal delivering roll stand and a metal receiving roll stand, of a chute device disposed between said stands and comprising a movably mounted support normally disposed adjacent said delivering stand, a second movably mounted support normally disposed adjacent said receiving stand, a longitudinally movable chute carried by said first-named support, a longitudinally movable chute carried by said second-named support and disposed in continuation of said first-named chute and means for moving said 115 supports horizontally towards and away from each other to thereby respectively retract the chutes from, and advance them toward, the cooperating roll stands. 120
